UNITED STATES PATENT OFFICE.

EDWARD OVERTON JONES, OF BROOKLYN, NEW YORK, ASSIGNOR TO JOSIAH WEDGEWOOD & SONS, INC., OF AMERICA, OF NEW YORK, N. Y., A CORPORATION OF NEW YORK.

DESIGN FOR A PLATE OR SIMILAR ARTICLE.

Application filed July 14, 1927. Serial No. 22,751. Term of patent 14 years.

To all whom it may concern:

Be it known that I, EDWARD OVERTON JONES, a subject of the King of Great Britain, residing at 166 Hicks Street, Brooklyn, in the county of Kings and State of New York, have invented a new, original, and ornamental Design for a Plate or Similar Article, of which the following is a specification, reference being had to the accompanying drawing, forming part thereof.

It is understood that the decoration of which only half is shown, is continued around the circumference of the plate.

The figure is a plan view of a plate showing my new design.

I claim—

The ornamental design for a plate or similar article as shown and described.

In testimony whereof I have signed my name to this specification.

E. OVERTON JONES.
